UNITED STATES PATENT OFFICE.

GEORGE S. BLAKESLEE, OF CHICAGO, ILLINOIS.

POTATO-PEELING MACHINE.

1,039,689.

Specification of Letters Patent.

Patented Oct. 1, 1912.

Application filed September 25, 1911. Serial No. 651,102.

To all whom it may concern:

Be it known that I, GEORGE S. BLAKESLEE, a citizen of the United States, residing at Chicago, in the county of Cook and State 5 of Illinois, have invented certain new and useful Improvements in Potato-Peeling Machines, of which the following is a specification, reference being had to the accompanying drawings.

10 My invention relates to potato peeling machines of the type in which the peeling is removed by agitating the potatoes in contact with an abrasive surface, and has for its object to provide certain improvements 15 in the machine illustrated and described in my pending application Serial No. 539,144, filed January 20, 1910, in which the receptacle and the rotary bottom on which the potatoes or other articles to be operated 20 upon rest are composed throughout of abrasive material, such improvements relating particularly to the construction of the bottom as hereinafter set forth. I accomplish this object as illustrated in the drawings 25 and as hereinafter set forth.

What I regard as new is set forth in the claims.

In the accompanying drawings,—Figure 1 is a front elevation of my improved machine; Fig. 2 is a vertical section on line 30 2—2 of Fig. 1; Fig. 3 is a plan view of the bottom-plate; Fig. 4 is an under side view thereof; and Fig. 5 is an edge view thereof.

My improved machine comprises a stationary receptacle cylindrical in form and having an aperture at the top for the admission of the potatoes or other articles to be operated upon. Said receptacle also is provided with a bottom formed integral 35 with the sides and having a spout or discharge opening for the escape of water and parings,—the receptacle being mounted on a suitable stand or pedestal which carries mechanism for rotating the bottom-plate, 40 the latter being mounted in the lower portion of the receptacle upon the upper end of a vertical shaft driven either by hand or power through the driving mechanism above referred to. Both the receptacle and the ro-

50 tary bottom-plate are formed throughout of an abrasive substance composed of comminuted flint, or other suitable material, bonded together by cement or its equivalent substance that is of a lower degree of hardness than the flint, so that in use the bonding 55 material disintegrates more rapidly than the abrasive substance proper and consequently the abrading surface is always sharp and effective. By this construction the machine is made practically indestructible and can- 60 not wear out since the walls of the receptacle and the bottom-plate are made of such thickness that it is practically impossible to wear them out.

In my present invention a bottom-plate 65 of improved construction is provided to assist in moving the potatoes or other articles out toward the inner wall of the receptacle so as to bring them more effectively into contact therewith, and also to cause the articles operated upon to roll over and thereby insure their being peeled completely. This is accomplished by making the bottom-plate 70 conical in form through the greater portion of its area, the upper surface sloping down- 75 ward to a point near the margin, which is comparatively flat. Small recesses or cups are provided, preferably at diametrically opposite points adjacent to the margin, which, in the rotation of the bottom-plate, 80 has the effect of causing the potatoes to roll more or less and thereby insure the proper peeling thereof.

Referring to the drawings for a description of the embodiment of my invention 85 therein shown,—6 indicates the cylindrical receptacle in which the potatoes or other articles are placed, said receptacle having an integral bottom 7 provided with a spout or outlet 8, as shown in Fig. 2. The receptacle 6, including the bottom 7, are made integral and are composed of comminuted flint or other suitable hard substance mixed with cement or other suitable bonding material.

9 indicates an additional outlet adjacent to the bottom 7, the upper surface of said bottom being inclined in opposite directions

toward the outlets 8—9 for the discharge of water and peelings.

10 indicates a door provided at one side of the receptacle 6 and also formed of the same material.

11 indicates standards or legs which support the receptacle 6.

12 indicates the inlet opening at the top of the receptacle. The legs 11 are prefer-

ably made adjustable vertically so as to provide for regulating the height of the receptacle 6 to any desired extent.

13 indicates cross-braces connected with the several legs and forming supports for the driving mechanism.

14 indicates a vertical shaft mounted in suitable bearings on the braces 13 and extending up through a bearing 15 in the bottom 7. The shaft 14 is provided with a beveled pinion 16 which meshes with a beveled pinion 17 carried by a shaft 18 and provided with a hand-wheel 19, or other suitable means for rotating the same, as shown in Figs. 1 and 2.

25 20 indicates a water-pipe communicating with the upper portion of the receptacle.

21 indicates the rotary bottom-plate, which is composed of the same material as the receptacle 6 and is mounted upon the upper 30 end of the shaft 14 and connected to it so as to rotate therewith. As shown in Figs. 2, 3 and 5, the upper surface of the bottom-plate is made convex or conical, sloping downward toward the margin thereof.

35 22 indicates recesses or cups in the bottom-plate 21 adjacent to its margin, said recesses being large enough to receive a potato, apple, or other similar article. The marginal portion of the bottom-plate between the recesses 22 is substantially flat, as shown at 23, in Fig. 3.

40 24 indicates a handle for lifting the bottom-plate out of the receptacle when desired, as for cleansing purposes.

45 When the potatoes or other articles are placed in the receptacle they rest upon the bottom-plate 21. By rotating the latter the potatoes are caused to roll more or less upon the bottom and are also carried around in 50 contact with the inner wall of the receptacle so that by the action of the abrasive surfaces they are effectively pared, the parings, and water which is supplied during the operation, escaping through the outlets 8—9.

55 That which I claim as my invention, and desire to secure by Letters Patent, is,—

1. A peeling machine, comprising a suitable receptacle having an abrasive inner wall and a rotary bottom-plate therein composed 60 throughout of abrasive material and a suitable bonding substance, said bottom-plate having one or more cups or recesses formed in the upper surface thereof, and means whereby said bottom-plate may be rotated.

2. A peeling machine, comprising a suitable receptacle having an abrasive inner wall and a rotary bottom-plate therein composed throughout of abrasive material and a suitable bonding substance, said bottom-plate having one or more cups or recesses formed 70 in the upper surface adjacent to the margin thereof, and means whereby said bottom-plate may be rotated.

3. A peeling machine, comprising a suitable receptacle having an abrasive inner 75 wall and a rotary bottom-plate therein composed throughout of abrasive material and a suitable bonding substance, the upper surface of said bottom-plate being inclined 80 downward from the center toward the margin thereof, and one or more recesses or cups in the upper surface of said bottom-plate adjacent to its margin.

4. A peeling machine, comprising a suitable receptacle having an abrasive inner 85 wall and a rotary bottom-plate therein composed throughout of abrasive material and a suitable bonding substance, said bottom-plate having cups or recesses formed in the upper 90 surface adjacent to the margin thereof, and means whereby said bottom may be rotated, the marginal portion of said bottom-plate between said recesses being substantially flat.

5. A peeling machine, comprising a suitable receptacle having an abrasive inner wall and a rotary bottom-plate therein composed throughout of abrasive material and a suitable bonding substance, the upper surface of said bottom-plate being inclined downward from the center toward the margin thereof, and one or more recesses or cups 10 in the upper surface of said bottom-plate adjacent to its margin, the marginal portion of said bottom-plate between said recesses 10 being substantially flat.

6. A bottom-plate for peeling machines, comprising a disk composed of an abrasive substance and a suitable bonding material, the upper surface of said disk being inclined 11 downward from the center toward the margin thereof, and one or more recesses or cups in the marginal portion of said plate.

7. A peeling machine, comprising a suitable receptacle having an abrasive inner 11 wall and a rotary bottom-plate, said bottom-plate having one or more cups formed in its upper surface adjacent to the margin thereof.

8. A peeling machine, comprising a suitable receptacle having an abrasive inner wall and a rotary bottom-plate, said bottom-plate having one or more cups formed in its upper surface adjacent to the margin thereof, the upper surface of said bottom-plate 11 being inclined downward from the center toward the margin thereof.

9. A bottom-plate for peeling machines,

comprising a disk having an abrasive upper surface and provided with one or more recesses adjacent to the margin thereof.

upper surface of said disk being inclined downward from the center.

10. A bottom-plate for peeling machines,
5 comprising a disk having an abrasive upper surface and provided with one or more recesses adjacent to the margin thereof, the

GEORGE S. BLAKESLEE.
